UNITED STATES PATENT OFFICE.

NORMAN E. HARRIS, OF MURRAY, AND WILL D. SWIGGART, OF FULTON, KENTUCKY;
SAID SWIGGART ASSIGNOR TO SAID HARRIS.

LIFTING JACK.

Application filed March 10, 1921. Serial No. 451,137.

To all whom it may concern:

Be it known that we, NORMAN E. HARRIS and WILL D. SWIGGART, citizens of the United States, residing at Murray and Fulton, respectively, in the counties of Calloway and Fulton and State of Kentucky, have invented certain new and useful Improvements in Lifting Jacks; and we do hereby declare the following to be a full, clear, and exact 10 description of the invention, such as will enable others skilled in the art to which it appertains to make and use the same.

This invention relates to improvements in that type of devices termed lifting jacks especially adapted for use in connection with automobiles, while it is equally applicable for jacking up or lifting other wheeled vehicles in making repairs thereto or for other purposes for which it may be found applicable. 20

The invention has for its object to provide for applying or disposing the jack or device with greater convenience or facility to the vehicle or machine to be operated upon or repaired than has heretofore been practicable. 25

A further object is to provide for expediting the lifting or adjusting operation of the jack or device. 30

A still further object is to predetermine the relative movement between the screw-threaded members of the lifting or adjusting means or mechanism to guard against the liability of the mutilation or impairment 35 of the threads of said threaded members.

A still further object is to provide for facilitating the actuation of the ratchet and pawl instrumentalities in controlling the vertical movement of and positioning the swiveled jack-head in contact or engagement with the wheel axle or brake-drum shaft of a motor or automobile or other object to be elevated and sustained. 40

Other objects of the invention will be apparent from the following description of the construction, arrangement and operation of the parts or features thereof. 45

The invention therefore consists of certain instrumentalities and features of construction substantially as hereinafter more fully disclosed and defined by the appended claims. 50

The accompanying drawings illustrate the preferred embodiment, or one form, of our invention wherein it will be understood that various changes and modifications of the detailed construction and arrangement of parts may be made without departing from the spirit or scope thereof as covered by the claims, and in which drawings: 55

Figure 1 is a sectional elevation of the embodiment of my invention embracing the ratchet and pawl form thereof.

Figs. 2, 3 and 4 are detailed views thereof.

Fig. 5 is a sectional elevation of an embodiment of my invention wherein a mitre and worm-type of gearing are employed for actuating or adjusting the swivel-equipped barrel screw-threaded instrumentality. 65

Fig. 6 is a transverse section.

Fig. 7 is a fragmental vertical section of a modified form of the swiveled jack-head of the lifting instrumentality.

Fig. 8 is a side elevation of a wrench which may be used for actuating the worm and mitre gear actuating means for the lifting instrumentality. 75

Fig. 9 is a "brace-and-bit"-like implement for actuating the lifting instrumentality.

Fig. 10 is an end elevation of the worm- and mitre-gear spinning means for the lifting instrumentality. 80

As characteristic features of my invention, I provide as the direct lifting instrumentality an interiorly threaded exterior tubular member or barrel 1 and an exteriorly threaded member or screw 2 arranged within and adapted to actuate said first-referred-to member, similar to corresponding members or instrumentalities in my allowed application 85 filed September 10, 1919, Serial No. 322,803 in connection with which I employ certain other features which will now be described: The inner member or screw 2, together with the barrel or tubular member 1, is suitably secured upon a foot or base 3, the screw or member 2 having preferably a tenon let into a socket 4^a in said base, with a threaded lower end-extension upon which a nut 4^a is screwed up into and against the bottom of a recess 5 90 in the underside of said base, a feather or key 4^b being inserted into a slot 4^c formed partly in the side of said tenon and partly in the wall of said recess. The lower end of the

100

terminating tenon of the screw 2 is sunken into the recess 5 in the base 3, out of contact with the surface upon which the base rests for firmly retaining the screw in position in the base.

The upper end of the threaded barrel or tubular member 1 is suitably equipped with a swiveled head 6 preferably scooped out or concaved in its upper surface as at 6^a suitably to receive or form a supporting bearing for the axle of an automobile-axle, drum-shaft, or other object. The swiveling connection between the jack and the barrel or member 1 is effected preferably by means of a thrust-bearing member 7 partly let into the upper end of the tubular member or barrel and suitably supported thereon, it being suitably secured in place by a pin 8 inserted through the thrust bearing member and the barrel or member 1, said bearing member having seated, in concavities 9 therein, spherical bearing members or balls 10 upon which is mounted said jack-head, the latter having pivotal connection with the thrust-head or member 7 by means of a pivot 11 shouldered upon said thrust bearing as at 7^a and having an upper flanged end as at 7^b, the flange being received within and seated upon the shoulder 7^c of a counter-bore 7^d. By means of this form of jack-head 6 and arrangement of bearing spheres or balls 10 the load or weight is lifted in a vertical line inwardly of the resultant circle of the arrangement of said bearing spheres or balls and adapted to be received therein more or less equally all around the thrust-bearing and to the full lifting capacity of the jack. The screw 2 has a flange 8^a at its extreme upper end, just beyond the upper initial point of the terminal of its threads, the barrel 1 having a number of spiral threads 1^a extending from its lower end upwardly to, and terminating at 1^b, the relation between the flange 8^a and the upper terminal point 1^b being such that the inter-engagement of the full threads of the barrel-member 1 and the full threads of the screw or member 2 will be such that the movement of the barrel-member will be limited upwardly so that such inter-engagement will be discontinued at a point which would intercept projecting the barrel-member beyond the screw as to prevent the mutilation or injuring the teeth of said barrel and screw at their points of contact, as would be liable to otherwise take place.

A ratchet 12 is suitably housed as at 12^a upon the outer surface of the threaded barrel-member 1, the ratchet being milled out of the housing 12^a, the housing being arranged so as to allow of the turning or vertical adjustment of the barrel-member 1 independently thereof, a bottom-annular member 12^b, fitting freely around the barrel-member, being secured to the housing 12^a

preferably by means of a screw 12^c or otherwise, a suitable handle 13 being pivotally connected to said ratchet-housing 12^a for actuating the ratchet 12, the member 12^b serving as a washer for retaining the ratchet 70 operating means in effective relation with the ratchet.

The pawl or plunger 14 for engagement with the ratchet 12, has preferably a plurality of different or varying cross-sections or diameters, the purposes of which will be subsequently described.

The pawl or plunger 14 is housed or enclosed in a tubular extension 15 of the ratchet-housing 12^a, abutting the member 12^b, said pawl being arranged within said tubular extension in alinement with, and so as to have engagement with the ratchet 12 as seen in Fig. 1. The pawl or plunger 14 is equipped with a helical or coiled spring 16 encircling the same, so as to cause the pawl or plunger to automatically initially engage the ratchet teeth, the forward end of the pawl or plunger being formed with an irregular rear edged tooth 17, the right-lined face of the tooth when presented toward the perpendicular face of the ratchet-teeth effecting the holding action, the rear irregular or sloping edge thereof allowing of the slipping or snapping of the pawl or plunger tooth by the ratchet-teeth when the movement of the toothed or grooved barrel-member 1 is reversed. The differently-diamented portions of the plunger or pawl provide, it will be observed, for suitable clearance of the spring and the delivery of the pressure thereof upon the plunger and shoulders for the retention of the same in proper tensioned position. Also it will be noted that the plunger or pawl 14 has opposite right-lined or rectilinear faced portions 18 thereon and that the casing or tubular extension 15 has correspondingly contoured opposite portions 19 thereon to provide for cooperation with 18 to allow of changing the position of the plunger as desired in providing for changing the feed of the ratchet for either opening or closing the jack. The plunger or pawl 14 has fitted upon its outer end a tubular nut or cap 20 preferably by screw-threading the same upon said plunger or pawl 14 preferably by means of a pin or key 21 inserted transversely through orifices or passages 22 produced through said tubular extension or housing 15 and said plunger. The cap-nut is stepped at one end and adapted to be received within, and manipulated by applying thereto a suitable wrench for turning the cap-nut into fixed position upon the plunger or pawl, the cap-nut, however, being adapted to bear and turn upon the housing or tubular casing 15, as seen in Fig. 1. It will be noted that, from the foregoing arrangement, a "pinless" ratchet and non-pressing plunger is the re- 130

sultant, or obtainable thereby, a suitable leather or some suitable composition washer 23 being inserted in the bottom of the cap-nut 20 for suitably cushioning the plunger, 5 thus rendering the plunger and ratchet practically noiseless.

In the second embodiment of our invention, we employ, in connection with a like interiorly screw-threaded tubular or barrel-member 24 and a screw 25 within said barrel-member, a miter gear 26 for driving the barrel-member instead of by the pawl and ratchet, suitably housed in a flanged sleeve-like member 27 having suitably screwed to 10 its bottom-edge a flanged tubular member 27^a, as at 27^b slipped around or upon the barrel-member 24. The screw is secured to a base 28, the barrel-member 24 being applied to the screw, the screw being secured 15 in position as shown in the above described embodiment of my invention, namely by a nutted lower end tenon 29 of the screw and a feather or key 29^a inserted between the tenon and base, the nut applied to the tenon, 20 being designated as 29^b and received within a recess 29^c in the bottom of the base, with the lower end of the tenon removed within the base from contact with the surface upon which the base may rest for the purpose 25 disclosed in said above described embodiment of the invention.

The mitre-gear housing 27 is formed with an upwardly projecting tubular extension 30 within which is enclosed the barrel 24, said tubular extension having arranged upon its upper end a seat 31 for the swiveled jack-head 32, which jack-head has an upper bifurcated approximately ovoid surface, preferably to provide for readily seating the automobile or motor axle, or other object therein and preventing the inadvertent slipping of the thus supported object or weight. The jack-head seating member 31 rests upon a preferably polished steel washer 33 supported upon a thrust bearing member 34, the upper end of the tubular extension 30 encompassing the latter. A screw 35, with its head positioned in a counterbore or depression 36 in the jack-head 32 is threaded or screwed into an interiorly threaded tubular extension 37 of the jack-head, thus providing for the effective retention of the latter in position. The depression 36 is of a greater depth than to just receive the head of the screw, but is adapted to provide for the clearance of the screw head as indicated at 38, in allowing for the vertical adjustment of the jack-head according to the angularity of positioning the same, as may be required for applying the jack to the axle or shaft of an automobile or other motored vehicle in passing the means or wrench for actuating the jack laterally of or between the spokes of the wheel, as later indicated. An oil-duct 39 is pro-

vided at the upper end of the outer tubular extension 30 for passing oil or lubricant therethrough for lubricating purposes; also at 40 is a duct through the tubular extension for a like purpose and at a point intermediate said member and the barrel-member 24 is a groove 41 for the same purpose.

The screw 25 is also provided at its extreme upper end with a flange 42 and the barrel member 24 is provided in like manner as the corresponding element 1 of the aforesaid embodiment of the invention, with a spiral thread 43, said flange and said spiral thread being co-operative for the same purpose as indicated in said embodiment.

A worm 44 meshes with the miter gear 26, its journal 44^a being supported within sectional or halved-together bearing 45, supported from the casting of the miter gear and suitably held together preferably by headed screw-threaded bolts 46. The journal 44^a of the worm 45 is equipped at one end, as disclosed by Figs. 5 and 6, more particularly, with a spherically-shaped head 47, which is so contoured however, as to provide square or quadrangular formations thereon for the application thereto of the correspondingly shaped socket of a wrench, as is obvious and which will be apparent from the subsequent description. Extending longitudinally through the worm-journal and the nut-shaped formation, is a passage 48, as indicated in dotted lines in said figures, adapted to receive a sliding or retractile vise-like operating lever or instrumentality 49, as indicated partially in dotted lines and partially in full-lines. Said instrumentality or lever, it will be seen, is adapted to be slid or retracted within the

passage 48 of the worm-journal 44^a, having suitable end retaining cap-members as seen, when not in effective use. Said lever or instrumentality has spherical terminals 49^a, one of which is adapted to be housed and slid within the passage 48 and allow of the movement of the lever at right angles to the axis of the worm and be retained against inadvertent displacement as also indicated in dotted lines in Figs. 5 and 6, the other spherical terminal of the lever is adapted to be seated as at 49^b in the spherical terminal 47 of the worm-journal 44^a when the lever is in its retracted position, as also seen in said figures. By means of this arrangement, it will be observed that, by suitably extending the lever 49, as indicated in dotted lines, and grasping and whirling or imparting a rapid twirling movement thereto, the worm will be accordingly given an accelerated movement and provide for imparting a quick or speeding action to, and thus rapidly "run" up the barrel-member with the jack-head; any slight slackness can be readily remedied by suitably tapping the jack-head. In event of breaking the lever

49, a nail, as 50 or other instrumentality convenient for the purpose, may be used or impressed into service.

As indicated in Fig. 8 a wrench-member 5 or spindle 51 may be applied to the squared nut-like formation of the worm journal 44^a and a suitable handle adjusted to the end thereof of angular-outline as at 51^a for operating the jack. In applying the jack for 10 use laterally of the automobile or other wheeled motor or machine which would obviate operating the jack thereunder, a brace-and-bit like instrumentality as at 52, as shown in Fig. 9, may be employed, the 15 socket end 52^a thereof being applied to the quadrangular formation of the worm-journal 44^a, said instrumentality being previously passed between the wheel-spokes and the jack-head suitably adjusted to the axle 20 or shaft; the handle or brace of the instrumentality is now positioned at the chest and the crank or intermediate portion of the instrumentality grasped and suitably manipulated as in operating this type of well-known device employed in actuating an 25 auger, thus effecting the jacking-up operation with convenience and facility and without the trouble, stress and unsanitary conditions heretofore attending the same.

30 In the modification as disclosed by Fig. 7, is shown a swiveled jack head 53, which has a plurality of equidistantly arranged teeth 54, around its base or bottom edge adapted to be received within a plurality of 35 sockets 55 in the barrel-member; the teeth when withdrawn from these sockets, as is the case when the jack-head 53 is elevated out of its seat, allows the latter to be disposed at the desired angle and locked at 40 such angle by again effecting engagement between these teeth and their sockets; this arrangement thus provides for disposing the jack-head to the automobile-axle to cause it to aline or parallel said axle, also to provide 45 clearance for the jack-head in case of the presence of an otherwise obstructing brake-shaft drum.

In a counterbore 56 in the swiveled jack-head 53 is a headed screw 57 threaded into 50 a depending portion 58 of the barrel member 59 for the providing for the vertical adjustment of the jack-head.

We claim:

55 1. A jack or device of the type described comprising an interiorly screw threaded barrel having an annular concaved bearing portion at its upper end, antifriction members in said concaved bearing portion, a

jack head swiveled on said bearing portion and rotatably supported on said antifriction members, a screw within said barrel, and means for actuating said barrel with respect to said screw.

2. A jack of the type described, including an interiorly threaded barrel-member having a jack-head at its upper end, a screw-engaging the thread of said barrel-member, a ratchet-member, a plunger engaging said ratchet, and a housing for said plunger and ratchet-member, said plunger member having a plurality of stepped transverse sections, one having opposite plane surfaces or faces engaged by opposite corresponding surfaces of the plunger housing.

3. A jack of the type described, including an interiorly-threaded barrel-member, a screw engaging the threads of said barrel-member, a ratchet-member, a plunger engaging said ratchet-member, a substantially common housing for said plunger and ratchet-member having said barrel-member passing freely therethrough, said housing having a cap-nut applied to one end thereof and threaded upon said plunger, and means for the retention of said cap-nut upon said housing.

4. A jack of the type described, including an interiorly-threaded barrel-member, a screw engaging the threads of said barrel-member, a ratchet-member, a plunger engaging said ratchet-member, a substantially common housing for said plunger and ratchet-member having said barrel member passing freely therethrough, said housing having a cap-nut applied to one end thereof and threaded upon said plunger, and means for the retention of said cap-nut upon said housing, and a resilient member arranged between said plunger and its housing, clearance therefor being provided by a stepped enlargement of said housing.

5. A jack of the type described including a threaded barrel-member provided with a jack-head, means engaging the threads of said barrel-member, said jack-head provided with a vertically adjusting member received thereinto and threaded into said barrel-member, said jack-head and barrel-member being provided with interengaging teeth and sockets for the retention of said jack-head in effective position against inadvertent turning.

In testimony whereof, we affix our signatures.

NORMAN E. HARRIS.
WILL D. SWIGGART.
